UNITED STATES PATENT OFFICE

2,664,655

SADIRON LIFT

Ivar Jepson, Oak Park, Ill., assignor to Sunbeam Corporation, Chicago, Ill., a corporation of Illinois

Application May 19, 1948, Serial No. 28,018

5 Claims. (Cl. 38—79)

1

This invention relates to an improved mechanism for supporting a flatiron above a work-holding surface, such as an ironing board, whenever the iron is not in use.

In certain types of flatirons it is the usual practice to set the iron up on its rear end on the ironing board when the ironing operation is temporarily stopped. In certain other types the iron is tipped over on its side. This practice is objectionable in several respects in that it causes wear and strain on the cord which is twisted more than 90° from its normal position; it exposes the entire heating surface of the sole plate so that it may be brushed against by the user's arm; and this up-ended position is relatively unstable whereby the iron may fall off the ironing board, thus presenting a further hazard especially to small children. Furthermore, certain types of steam irons cannot be up-ended or rolled over on their side without creating an undesirable condition in the water reservoir which should preferably be maintained in a level condition. It is preferable, therefore, that the iron not be tipped in the out-of-use position. Accordingly, a primary object of the present invention is the provision of a novel flatiron support which is simple, compact, relatively inexpensive to manufacture and which positively maintains the iron supported in a preselected position spaced above the working surface.

Other objects and advantages will become apparent from the following description in connection with the drawings, in which—

Figure 1 is a side view of a flatiron made in accordance with the present invention showing the supporting levers in an extended position to support the iron above the ironing surface;

Fig. 2 is a bottom view of the flatiron shown in Figure 1;

Fig. 3 is a cut-away top view of the iron showing a top view of the supporting levers in their retracted positions;

Fig. 4 is a longitudinal sectional side view taken along the line 4—4 of Fig. 3 and showing the supporting levers in both extended and retracted positions;

Fig. 5 is a transverse sectional view taken along the line 5—5 of Fig. 3; and

Fig. 6 is a fragmentary longitudinal sectional view taken along line 6—6 of Fig. 3.

Referring now more particularly to the drawings, the invention is shown embodied in a flatiron comprising a body generally designated 1 and a handle 2 fixedly secured thereto, the latter carrying the heat regulating control wheel 3 of

2

conventional construction. It is to be understood that the iron is provided with a heat control mechanism as well as electrical leads; however, they have been omitted from the drawings to show the present invention more clearly.

The body 1 includes the usual sole plate 4 and cover 6 which in the present instance extends beyond the rear of the sole plate to provide a rearwardly extending hood 7 for a purpose to be hereinafter described. In this instance the sole plate 4 is a composite structure comprising the outer plate 8, inner plate 9, and heating element 11 interposed therebetween.

One aspect of the invention is concerned with novel means for maintaining the iron in spaced relation with the work piece when the iron is not in use, that automatically moves into a supporting position through the action of gravity when the iron is lifted vertically above the work piece and that returns to a retracted position due to the weight of the iron when the iron is moved forward from its supported position as in the normal ironing operation. Three supporting levers are employed in this modification for effecting the foregoing. The levers are conveniently and effectively spaced with respect to the iron by disposing one of the levers or iron supports 12 in a sole plate recess 13 disposed at a forward central position on the bottom of the iron and disposing two levers 14 in spaced relation mounted in suitable recesses formed at the rear of the iron.

The mounting for the levers 14 includes a bracket 16 having a generally L-shaped cross section secured to the hood 7 as by a rivet 17. To position the bracket 16 and provide additional support therefor its inturned flange 18 engages the extreme rear end of the hood 7 and its upstanding portion 19 abuts against the wall 21 at the rear of the body 1. Spaced apertures 22 permitting the passage of the support levers 14 are formed in the bottom portion 23 of the bracket 16. These apertures in effect define the recesses for the levers 14. On each side of each aperture is an inverted U-shaped bracket 24 secured to the bottom 23 as by welding and shaped to receive the ends of a pin 26 extending across the respective apertures. The pins 26 provide a pivot axis for the levers 14 which are mounted thereon. The pins 26 are dimensioned so that the levers 14 are freely movable relative to the pins 26 between a retracted position in which the levers 14 are received under the hood 7 as shown in Fig. 4 and an extended position in which the levers 14 extend downwardly from the sole

plate 4 as shown by the dotted lines in Fig. 4 to support the iron.

The forward lever 12 is also mounted for free movement about a pivot axis in the manner described for the levers 14. As shown in Fig. 3 short transverse slots are formed on the upper side of spaced upstanding ribs forming a part of the sole plate. These slots are on opposite sides of the recess 13 and a pivot pin 28 has its ends received in the slots 27 and is disposed with respect to the recess 13 so as to pivotally support the lever 12. The pin 28 is held in position by fingers 29 of a bifurcated clamp member 31. The latter is secured in position by a screw 33 received in a boss 32 projecting upwardly from the inner plate 9 adjacent the forward end of the recess 13.

The levers 12 and 14 in this instance are identical in size and shape so that when the iron is in a supported position the bottom surface of the sole plate 4 is in substantially parallel relation with a work surface 34 such as a piece of fabric disposed on an ironing board. Where desired the dimensions of either the front or rear supporting levers may be varied to vary the angle of repose of body with respect to the work holding surface 34 when the iron is in a supported position.

As shown in Figs. 4 and 6 the supporting levers 12 and 14 are generally triangular shaped and are mounted so that the pivot pins 28 and 26 respectively project through apertures in the levers located at the lower forward corner of each lever. This construction provides that when the iron is raised vertically from the work surface 34 the free ends 36 of the levers are pulled downwardly under the influence of gravity to a position forward of a vertical plane passing through the pivotal axis of each lever. This position of the levers is shown by the dotted lines in Fig. 4. In this instance the forward movement of the lever 12 is limited by engagement of the lever with the inclined end 37 of the sole plate recess 13 and the forward movement of the levers 14 is limited by engagement of the levers with the rear end 38 of the sole plate 4.

Since the levers 12 and 14 are urged downwardly by gravity to the supporting position when the iron is raised above the work surface 34 the levers of course will be urged downwardly during the ironing operation so as to press lightly on the work surface 34. To prevent the levers from becoming caught on the work surface 34 in either a forward or a backward movement of the iron, the lower surface 39 of each lever in its retracted position as shown in Fig. 4 is rounded or formed as a convex surface.

It is believed that the operation of the supporting mechanism may be readily understood from the foregoing paragraphs. Briefly, it is as follows: Assume that the iron is heated and is being used to iron a work piece. When it is desired to temporarily discontinue ironing it is only necessary to raise the iron vertically above the work surface 34. This permits the levers 12 and 14 to swing in a clockwise direction about their respective pivot axes by the action of gravity until the levers assume the positions shown by the dotted lines in Fig. 4. The iron is then lowered on to the work surface 34 and is supported in a level position at a uniform height above the work surface 34. In this position the weight of the iron presses the levers 12 and 14 into engagement with the end 37 of the recess 13 and the rear end 38 of the sole plate 4 re-

spectively. The free ends 36 of the levers are disposed forwardly of a vertical plane passing through the respective pivotal axes so that in effect the levers are in an overcenter position and the weight of the iron in effect locks the levers in this position. Subsequently when it is desired to continue the ironing operation the handle is grasped by the operator and the iron is pushed forward. This causes the levers 12 and 14 to rotate in a counterclockwise direction about their pivotal axes beyond the position in which the pivot pins 28 and 26 and free ends 36 of the respective levers are in vertical alignment. The iron, due to its own weight, then drops to its normal ironing position as shown in Fig. 4.

Thus, it will be seen that the present invention provides a supporting mechanism for flat irons wherein the user only has to lift the iron slightly and the iron will automatically be disposed in a self-supporting position with the sole plate 4 out of contact with the working surface 34. Moreover, when it is desired to resume use of the iron it is only necessary for the operator to grasp the handle and push the iron forward as is done in the normal ironing operation.

It will be apparent to those skilled in the art that the present invention is not limited to the particular construction shown but that changes and modifications may be made without departing from the spirit and scope of the present invention, and it is aimed in the appended claims to cover all such changes and modifications.

I claim:

1. In combination, a flatiron having a body formed with a plurality of downwardly facing recesses on its bottom ironing surface, a plurality of iron supports disposed respectively in said recesses, pivotal means mounted on said body adjacent the corresponding end of each of said recesses and pivotally supporting one end of the supports at said corresponding ends of each of said recesses, whereby said supports are freely pivotal about said pivotal means between a first limit position in which said supports are disposed wholly within said recesses and a second limit position in which said supports depend below said ironing surface, abutment means for each of said supports disposed at the ends of said recesses adjacent said pivotal means, said abutment means being engageable by said supports to define said second limit position of each of said supports, said abutment means for said support being located relative to said associated pivotal means to define said second limit position to one side of a vertical plane passing through the pivotal axis of said associated pivotal means whereby the weight of said flatiron holds said supports against said abutment means and said supports positively maintain the ironing surface of said flatiron above a work surface engaged by said supports.

2. The combination set forth in claim 1 in which the downwardly facing sides of said supports when disposed in said recesses in said first limit position define a convex surface between the mounted and free ends thereof to facilitate the passage of the flatiron over a work piece.

3. The combination set forth in claim 1 in which said pivotal means are each mounted at the ends of said recesses toward the forward end of said flatiron.

4. The combination set forth in claim 1 in which each of said supports is moved to the side of a vertical plane passing through the pivotal

axis of said associated pivotal means toward the forward end of said flatiron relative to said recesses and said supports are moved to their retracted positions within said recesses from their second limit positions solely by the forward movement of said flatiron while the free ends of said supports engage said work surface whereby the free ends of said supports move to the other side of the vertical planes passing through the pivotal axes of the respective supports and the weight of the flatiron automatically forces said supports into their respective recesses.

5. A flatiron comprising a body having an ironing surface and a handle for manipulating said flatiron, a downwardly facing recess in said ironing surface, a support, pivot means for pivotally mounting one end of said support within one end of said recess, said support and recess being so dimensioned that the free end of said support may be swung about the pivotal axis of said pivot means to a position wholly disposed within said recess, said pivot means being so disposed relative to said support that the force of gravity acting on said support moves said support out of said recess when said flatiron is lifted above 25

a surface engageable by said ironing surface, an abutment on said body engageable by said support and limiting the maximum movement of said support out of said recess to a position where 5 said support extends below said ironing surface, said abutment being disposed to limit the movement of said support beyond a vertical plane passing through the pivotal axis of said pivot means whereby the weight of said flatiron holds 10 said support against said abutment and the free end of said support, upon engaging a suitable supporting surface, holds said flatiron with said ironing surface above said supporting surface.
